UNITED STATES PATENT OFFICE.

HEDWIG SCHWIEGER, NÉE KIPP, OF HANOVER, GERMANY, ASSIGNOR TO HEINRICH GEERING, OF BASEL, SWITZERLAND.

CLOSURE FOR GLASSES FOR PRESERVED FRUITS AND THE LIKE.

1,427,128.

Specification of Letters Patent. Patented Aug. 29, 1922.

Application filed June 24, 1920. Serial No. 391,558.

To all whom it may concern:

Be it known that I, HEDWIG SCHWIEGER, NÉE KIPP, a citizen of the German Republic, and residing at Hanover, Germany, have invented certain new and useful Improvements in Closures for Glasses for Preserved Fruits and the like, of which the following is a specification.

With the known glasses containing preserved fruits and the like, the lifting of the lid from the glass, for the purpose of opening the latter, is rather difficult owing to the vacuum formed in the free upper part of the interior of the glass. The glasses can mostly be opened with great difficulty only, while they frequently break and particularly the tightening rubber washer between glass and lid becomes so much damaged that it cannot more be used afresh. Owing to the high costs of material, said drawbacks are of essential economical importance.

The present invention provides simple means by which said drawbacks are effectively overcome.

For this purpose, the lid of the glass has a depression, which is preferably centrally located therein and which is tapered, that is wider at the top than at the bottom, and which through a small orifice in its bottom is in communication with the interior of the glass. Said depression serves for the reception of a correspondingly shaped soft-rubber stopper therein, said stopper having either a narrow central slot-opening therein or being two-parted in its length and forming said slot-opening between said two parts. Said stopper is put in said depression of the lid during the boiling of the glasses with their contents therein and with the lids thereon, whereby the stopper is firmly sucked into said depression by the formation of the vacuum mentioned and the small orifice in the bottom of said depression is thus airtightly closed while at the same time also the narrow central slot-opening in the stopper is closed by the latter being contracted, or the two longitudinal halves of the stopper are firmly pressed upon one another so as to form practically one piece, as the case may be.

To open the glass, it is only necessary to spread the contracted stopper apart to open its narrow central slot-opening, so that at-

mospheric air is admitted to the interior of the glass through said slot-opening and through the small orifice in the bottom of the depression in the lid. Preferably, for this purpose, a small implement is used which consists of an annular handle and a bladelike member thereon, in which a longitudinal central bore with a lateral port is provided in such a way that, when the blade is pushed into the contracted narrow central slot-opening of the stopper, or between the two parts of the same, a communication is created through the bore in said implement between the interior of the glass and the outer air, whereby the latter is admitted to the vacuum in the glass, the latter is neutralized, and the lid can be easily lifted from the glass without damage to the same or to the tightening rubber washer between glass and lid.

The arrangement may also be such that a flat pin of any suitable material is put in the narrow slot-opening of the stopper, before the latter is inserted in the depression of the lid, and permanently left therein. By turning said pin on its own axis for 90°, the narrow slot-opening can be spread apart for the same purpose last above-mentioned, the pin returning after its liberation automatically to its initial position owing to the elasticity of the material of the stopper. The annexed drawing shows various appropriate constructional forms of the subject matter of the present invention.

Fig. 1 is a vertical central section through the upper part of a glass with its lid having a tapered depression with a soft-rubber stopper therein,

Fig. 2 is a fragmentary plan view of the same,

Fig. 3 shows the rubber stopper, in a side view and plan view respectively,

Fig. 4 shows the implement mentioned belonging thereto, in a front view and sectional side view respectively,

Figs. 5 and 6 are similar views to Figs. 1 and 2, showing the stopper with a flat pin inserted therein,

Fig. 7 is a similar view to Figs. 2 and 6, showing the upper opening of the conical depression in the lid covered by a stuck-on label for securing the lid against incompetent opening,

Figs. 8 and 9 are similar views to Fig. 3, showing the stopper and its flat pin belonging to the arrangement represented in Fig. 5,

Fig. 10 shows a two-part stopper in side views of the two parts, and Fig. 11 is a plan view of the latter:

Referring to Figs. 1 to 4 incl.:—3 designates the glass with an upper flange 2 on which the lid 4 is put by means of an intermediary rubber washer 1, as known in the art. 5 designates the tapered depression in said lid having a small orifice 6 in its bottom, through which it is in communication with the interior of the glass. 7 designates the soft-rubber stopper with a narrow central slot-opening 8 therein. 9 designates the implement for opening the stopper after its contraction as afore-described. For this purpose, the implement is with its blade-like member pushed through the narrow central slot-opening 8 until a communication through the central bore 10 and its lateral port 11 is created between the interior of the glass and the outer air, with the result described above.

In the example shown in Figs. 5 to 9 incl., the depression 12 of the lid 13 extends somewhat deeper and is so widened at its upper part that the flat pin 17, when inserted in the slot 15 of the stopper 16, lies with its handle 14 within said widened upper part in such a way that it can be caught by hand for turning the pin 17 for the purpose afore-mentioned.

As shown in Figs. 10 and 11, the stopper may consist of two longitudinal halves 18 and 19, in which indentations 20 for the formation of the narrow slot-opening therein are provided.

To secure the lid against incompetent opening, a label 21 (Fig. 7) may be stuck over the upper opening of the depression 5 (Fig. 1) or 12 (Fig. 5), which label may at the same time serve for inscriptions indicating the date of filling, or the nature of the contents in the glasses, or the like. The glasses can be put above each other, as the upper surface of the lid is completely smooth.

The depression 5, or 12, in the lid is cup-shaped at its bottom, whereby a small free space is left between the latter and the lower end of the stopper.

A great advantage of the improved arrangement lies in the fact that the contents of the glass cannot come in contact with the rubber stopper in the depression of the lid.

What I claim is:

1. In a closure for glasses for preserved fruits and the like, in combination, a lid having a tapered depression therein with a small orifice in its cup-shaped bottom, a soft-rubber stopper of corresponding formation in said depression having a narrow central slot-opening therein, and an opener for an eventual insertion in the slot-opening of said stopper consisting of an annular handle and a blade-like member having a central bore with a lateral port therein, substantially as and for the purpose set forth. 70

2. In a closure for glasses for preserved fruits and the like, in combination, a lid having a tapered depression therein with a small orifice in its bottom, a soft-rubber stopper of corresponding formation in said depression having a narrow central slot-opening therein, and an opener for a permanent insertion in the slot-opening of said stopper consisting of a flat pin turnable on its own axis, substantially as and for the 80 purpose set forth. 75

In testimony whereof I have hereunto set my hand in the presence of two subscribing witnesses.

HEDWIG SCHWIEGER, NÉE KIPP.
